VACUUM CLEANER

Ernst Faber, Stuttgart, Germany

Application November 17, 1937, Serial No. 175,121
In Germany November 25, 1936

1 Claim. (Cl. 183—35)

This invention relates to a vacuum cleaner with an outer casing, a motor fan unit arranged therein, an indiarubber ring arranged in the outer casing in front of the motor fan unit, against which ring the motor fan unit bears, and a removable cap, which closes the outer casing at its rear end.

The object of the present invention is to improve this known structure in such a way as to provide a particularly simple method of supporting the motor fan unit, so as to enable this unit to be quickly and conveniently put in or taken out.

Accordingly the removable cap that closes the outer casing at the rear end is of such concave shape that it directly forms an abutment for the rear end of the motor fan unit.

The removal of the rear closure cap of the casing enables the motor fan to be readily put in position or taken out.

One embodiment of a vacuum cleaner according to the invention is illustrated by way of example partly in outside elevation and partly in longitudinal section in the accompanying drawing.

In this drawing *a* denotes the body of the vacuum cleaner casing, which is provided at the front end with a removable cap *b* having an air suction aperture *c*, and at the rear end with a removable cap comprising elements *d*, *m*, *r*, *n*, and an air discharge aperture *e*. In the casing is yieldingly arranged the motor fan unit *f*, which bears loosely at its front end against an indiarubber ring *g* mounted in the vacuum cleaner casing. In front of the motor fan unit a dust bag *h* is provided in the outer casing of the vacuum cleaner. The part *d* of the rear closure cap is made of insulating material, an artificial resin for example, and is secured in a readily detachable manner by means of a number of screws *i* arranged on its periphery to a metal ring *k*, which in its turn is arranged upon the body *a* of the casing. At its free end the part *d* carries a sheet metal insertion *m*, which is dished in such a way as to form at the same time the rear abutment *n* for the motor fan unit, a cavity *o* for the accommodation of a supplementary filter *p*, *q*, *p'* removable at the rear, and a tubular element *r* for mounting a cover *s* provided with a discharge aperture *e*. The abutment *n* has a central aperture *w* for accommodating the rear end *t* of the motor fan unit, and is also provided with apertures *u* for the passage of air. The arrows indicate the direction of flow of the air. The supplementary filter consists of a thick layer *q* of filtering material, made of wadding for instance, and suitably saturated with a disinfectant, a perfume or the like, and of two sheets *p*, *p'* of wire

gauze or wire netting loosely arranged in the cavity *o* to hold and stiffen the layer of filtering material. One of these stiffening layers, through which air can pass, bears against the bottom of the cavity *o*, and the other is held in contact with the filtering material *q* by abutment bolts *v* projecting forwards from the cover *s*.

For the purpose of exchanging the supplementary filter all that is necessary is to remove the cover *s* from the tubular mounting connection *r*, upon which it may be secured by friction or otherwise, the outer strainer or sieve *p* also being removed, whereupon the layer of filtering material *q* can be replaced by a fresh one. On the other hand the unscrewing of the part *d* from the ring *k* enables the motor fan unit to be released quickly and taken out.

The cap *d*, *m*, *r*, *n*, may be made entirely of sheet metal. The front sieve plate *p* may be replaced by a ring bearing on the outer margin of the layer of filtering material, or may be entirely omitted. In the latter case the frustoconical portion *n* is preferably so shaped as to form at the margin an annular flange supporting the layer of filtering material. The simple marginal supporting of the actual filtering layer is sufficient, having regard to the pressure exerted by the air upon the filtering layer when the vacuum cleaner is in operation to press the filtering layer against the rear supporting sieve *p'*. This last-named sieve or perforated plate may be fixedly mounted on the supporting bolts *v* and may then be taken off or put on along with the cover *s*. An important feature is the sub-dividing of the filter into the filtering layer, removable by itself, and capable of being cheaply manufactured, preferably of wadding or some similar pliable material, and a supporting sieve or perforated plate or the like pressed by means of the mounting cover against this filtering layer. The wadding enables the filter to absorb a large amount of disinfectant or the like, thus giving satisfactory and effective filtering over a long period, besides considerably improving the damping of noise.

What I claim is:

A vacuum cleaner, comprising an outer casing, a motor fan unit enclosed in the outer casing, an indiarubber ring lodged in the outer casing in front of the motor fan unit, the motor fan unit bearing against the indiarubber ring, and a detachable cap closing the casing at the rear end, the detachable cap being of such concave shape as to form directly an abutment bearing against the rear of the motor fan unit.
